UNITED STATES PATENT OFFICE

170,113

PUZZLE

George de Sibrik and Ilona de Sibrik,
Washington, D. C.

Application September 4, 1952, Serial No. 21,333

Term of patent 7 years

(Cl. D34—15)

To all whom it may concern:

Be it known that we, George and Ilona de Sibrik, citizens of Hungary, residing at Washington, D. C., have invented a new, original, and ornamental Design for a Puzzle, of which the following is a specification, reference being had to the accompanying drawing, forming part thereof.

Figures 1, 2, 3, and 4 are plan views of a puzzle showing our new design.

The puzzle consists of 36 square cards of no appreciable thickness, the backs of which are unornamented or of conventional appearance.

We claim:

The ornamental design for a puzzle, as shown and described.

GEORGE DE SIBRIK,
ILONA DE SIBRIK.
